HINGE MEMBER FOR CARDS

Filed Nov. 16, 1925

FIG. 2

FIG. 4

INVENTOR

George H. Dawson

George H. Dawson

UNITED STATES PATENT OFFICE

GEORGE HIVES DAWSON, OF CAMBRIDGE, MASSACHUSETTS, ASSIGNOR, BY MESNE ASSIGNMENTS, TO REMINGTON RAND INC. OF NEW YORK, N. Y., A CORPORATION OF DELAWARE

HINGE MEMBER FOR CARDS

Application filed November 16, 1925. Serial No. 69,356.

This invention relates to a card carrier primarily designed for use in visible overlapping indexes and concerns itself particularly with the manner of constructing the hinge member constituting a part of the carrier, so that the same may be readily creased upon a straight line parallel to the supporting bar of the carrier.

In the use of such card carriers, a large number are generally supported in a tray and the cards are removably supported upon the hinge members thereon. These cards frequently have to be turned upwardly in reversed position and it is desirable that the hinges of the different cards flex in parallel straight lines in order to maintain an orderly array.

In the past it has been proposed to use a stiff hinge member such as kraft paper and weaken the same along a horizontal space or section by a series of rectangular or square apertures or slots punched therefrom. It has been found in practice that the weakened area or section resulting therefrom would not always crease in a line parallel to the supporting bar of the hinge member due to the fact that the total apertured section is equally weakened. Frequently the hinge crease would extend obliquely to the supporting bar causing a disorderly array when the cards are swung upwardly into reversed position. In order to overcome this objection, a series of trapezoidal or other similar apertures are punched in the cards providing thereby a variably weakened section, having its line of least resistance parallel with the supporting member of the hinge, consequently when a hinge member is folded for creasing purpose, the fold and crease will occur at the line of least resistance.

The invention comprises the novel structures and combinations hereinafter described and more particularly pointed out and defined in the appended claims.

In the accompanying drawings which illustrate certain preferred embodiments of this invention and in which similar reference numerals refer to similar features in the different views:

On the drawings:

Figure 1 is a plan view of a card carrier embodying this invention;

Fig. 2 is an end elevational view of the carrier;

Figures 3 and 4 are fragmentary plan views of modifications of punched out sections in accordance with this invention, and

Fig. 5 is an enlarged fragmentary plan view of the hinge member shown in Figure 1.

As shown on the drawings:

The invention in one of its broadest aspects comprises a fairly stiff hinge member, preferably of paper, or the like, which is varyingly weakened by a series of apertures which have the characteristic of creating a line of least resistance for creasing purposes parallel with the supporting bar of the hinge member.

In illustrating the invention, there is shown a spacing bar 1 which is adapted to fit in the guideway of a tray or the like as is well known in the art. A hinge member 2 is attached to this spacing bar in any suitable manner. In the present instance this hinge member consists of some fibrous material as kraft paper which is sufficiently strong, stiff and durable for such a purpose. However, any other suitable stiff material may be used. In the present instance the hinge member is designed for supporting two index cards and for this purpose it is supplied with two pairs of eyeleted disks 3 and 4 from which the cards may be suspended. It should, however, be understood that the hinge member may be constructed to support a lesser or a greater number of cards as desired.

Adjacent and parallel to the spacing bar 1, the hinge member 2 is variably weakened by a longitudinal series of similarly directed apertures having diverging wall portions extending transversely of the series. These apertures may be in the form of trapezoids 5, as shown in Figures 1 and 5, or in the form of triangles 6, as shown in Figure 3, or may be of segmental form 7, as shown in Fig. 4. However, any other form of apertures may be used that will provide a variably weakened longitudinal section, having a straight line of least resistance parallel to the supporting

bar 1 for forming a hinge crease. When two cards are to be supported in spaced relation upon the same hinge, a second weakened section spaced from the first may be provided as shown to form a second hinge crease.

It will be appreciated that the diverging wall portions which will be designated as 8, 9 and 10 in the different forms of weakening apertures and which extend transversely of

10 the series provide varyingly weakened sections in that the material left between the apertures decreases from one side of the section to the other. In the present instance, the weakening apertures are so directed that

15 the least material is left along the upper side of the section denoted by the reference 11. That is to say, the portions of the material between the apertures 5 and which connect the sections of the hinge disposed above and

20 below the line of apertures are narrower at the top than at the bottom. From the upper line 11 of the sections, the material between the apertures increases to the lower line of the weakened section. Consequently the line

25 11 of least material, constitutes the line of least resistance. As the illustrated apertures are symmetrical, the weakened section is progressively weakened from the lower side to the upper side as is apparent.

30 By providing a varyingly weakened section, so that there will be a line of least resistance, it will be appreciated that the hinge members will always fold along such line. It might be mentioned that the carriers are

35 manufactured as shown in Figure 1. They are then passed to the creasing operator that manually creases the same. This creasing operation is performed by simply folding the hinge members at the weakened section.

40 In such operation the hinge crease will always take place along the line of least resistance, which is parallel to the supporting bar 1. Consequently according to this invention the supported cards when reversed will always assume an orderly array and not lie obliquely to each other.

I am aware that many changes may be made and numerous details of construction may be varied through a wide range without departing from the principles of this invention, and therefore do not purpose limiting the patent granted thereon otherwise than necessitated by the prior art.

I claim as my invention:

55 1. In a card carrier, a supporting member, a relatively stiff paper hinge attached to said member and provided with a straight series of apertures having diverging straight wall portions for producing a narrow weakened section having a varying resistance with the line of least resistance parallel to said supporting member.

60 2. In a card carrier, a supporting member, a paper hinge attached to said member and having a series of similarly directed trape-

zoidal slots providing a varied weakened section having its line of least resistance parallel to said member.

3. An article of manufacture, comprising a fibrous hinge strip having a series of apertures provided with diverging straight wall portions whereby a varyingly weakened section is formed providing a straight line of least resistance for creasing purposes. 70

4. An article of manufacture, comprising a fibrous hinge strip having a series of similarly directed trapezoidal apertures for providing a weakened section of varying resistance with a single line of least resistance. 75

5. An article of manufacture, comprising a fibrous hinge strip having a series of similarly directed apertures with diverging straight walls providing a transversely progressively weakened hinge section with a line of least resistance for forming a hinge 80 crease. 85

6. In a card carrier, a supporting member, a fibrous hinge strip secured to said member and having a longitudinal series of similarly directed apertures with diverging straight wall portions providing a progressively weakened hinge section having a line of least resistance for forming a hinge crease. 90

7. An article of manufacturing comprising a supporting member, a fibrous hinge on said supporting member having a plurality of parallel weakened sections, and a set of card-supporting means on said hinge in like relation to each of said sections respectively, for independent hinge action of each card. 100

8. An article of manufacture comprising a supporting member having an extended fibrous hinge member provided with a plurality of varying weakened portions dividing the member into upper and lower sections, 105 and a pair of card-supporting members on each section, said weakened portions adapted to provide independent hinge action for each of said sections and the cards thereon.

9. An article of manufacture, comprising a fibrous hinge strip provided with a series of apertures each having a straight wall portion in aligned relation and said series of apertures having a dimension parallel to said wall portion that varies in a direction laterally from said straight wall portions to provide a weakened hinge section of variable resistance having a line of least resistance adjacent said straight wall portions. 110

10. In testimony whereof I have hereunto subscribed my name.

GEORGE HIVES DAWSON.
